TYPEWRITING MACHINE

Henry L. Pitman, Hartford, Conn., assignor to
 Underwood Elliott Fisher Company, New York,
 N. Y., a corporation of Delaware

Application March 27, 1939, Serial No. 264,377

14 Claims. (Cl. 197—66)

This invention relates to typing machines employing a carriage, and more particularly to returning the carriage by power and gaging the return to different line-start defining positions.

The general object of the invention is to provide an efficient, simple mechanism enabling the typist easily and selectively to gage the power return of the carriage to different positions at will.

The invention employs a plurality of carriage return keys corresponding to the number of different line start positions, each key being effective to initiate a return of the carriage by power from a position to which it has been advanced by letter feed or tabulating. A carriage return limiting stop is associated with each key.

The operation of one key causes its associate stop to be effective to gage the return of the carriage, say, to an extreme position. Another key causes its associate stop to gage the return of the carriage to an intermediate position. Still another key may cause an associate stop to gage return of the carriage to a different intermediate position. The invention is not limited to determining three return positions of the carriage since, as will hereinafter be obvious, the invention is applicable to determine two positions, or to determine four or more positions.

The several carriage return keys are selectively operable by the typist and may be disposed at or in the vicinity of the typewriter keyboard.

Another object of the invention is to have the return positions of the carriage determinable separately as, for example, by separate adjustments of the stops along the direction of carriage travel in the manner of adjusting a conventional margin stop. This affords the advantage that the distances between the several positions to which the carriage is selectively returnable may be adjusted or varied at will.

Another object is to have the application of power to return the carriage stopped automatically consonantly with the engagement of one or another of the aforesaid separately adjustable stops with a suitable counter-stop, and further to have said engagement effective to stop said application of power irrespective of whether the actuated key happens to continue to be depressed by the typist at the instant of said engagement.

Each intermediate carriage return stop is preferably normally out of operative alignment with a counter-stop. The carriage return stop for gaging extreme return of the carriage may be constantly in alignment with a counter-stop. Thus, operation of the carriage return key asso-

ciated with the extreme stop determines return of the carriage to the extreme position.

The invention employs means whereby depression of an intermediate carriage return key determines operative alignment of the associate intermediate stop with the counter-stop and, in conjunction with this, the invention provides means whereby upon depression of the intermediate key the associate intermediate stop and counter-stop device become automatically maintained in operative alignment independently of said intermediate key so that the typist need not keep said intermediate key depressed.

Another feature is in means whereby the stop-maintaining means are automatically disabled and the intermediate stop is automatically caused to be restored to ineffective position relatively to the counter-stop consequently to said intermediate stop having functioned to stop the return of the carriage at the intermediate position. This disablement of the stop-maintaining means may be accomplished irrespective of whether the typist happens to keep the intermediate key depressed instead of releasing the key before the automatic restoration of the intermediate stop occurs.

Another feature of the invention resides in improvement in means heretofore used to enable the carriage as it reaches a line end position to automatically initiate a power return of the carriage.

Another object of the invention is to embody it in means readily applicable to existing designs of machines such as the Underwood Standard typewriter.

The foregoing and other objects, features and advantages will be apparent from the following description.

In the accompanying drawings:

40 Figure 1 is a perspective diagram of a part of the connections enabling the carriage, as it reaches a return position, to disconnect itself from the power drive.

45 Figure 2 is a cross sectional side elevation showing the application of the invention to a typewriter, only such known parts of the latter being shown as are necessary to illustrate the invention.

Figure 3 is a front elevation showing the machine frame and supports associated with the carriage stop mechanism.

Figure 4 is a perspective diagram of a part of the connections whereby the carriage initiates a return of the carriage automatically.

Figure 5 is a fragmentary side view showing

details of a latch device and related parts for maintaining an intermediate stop in effective position.

Figure 6 is a perspective illustrating the several carriage return keys and connections to the intermediate return stops, only one of the latter being shown.

Figure 7 is an extension of Figure 5 showing another intermediate carriage return stop and extreme carriage return stop.

Figure 8 is a perspective of two intermediate stops combined for joint adjustment.

Figures 9, 10 and 11 are side view diagrams showing the relative positions of the parts consequent to operation of the different carriage return keys.

In a typewriter such as the Standard Underwood, a carriage 15 moves laterally on front and rear tracks 16, 17 supported on the machine frame partly shown at 18, Figure 2.

A spring motor 19 urges the carriage leftward in letter feed steps under the control of escapement dogs 20 cooperative with an escapement wheel 21 having a pinion 22 meshing with a letter feed rack 23 on the carriage.

Type bars 24 are actuatable by means of type keys 79 to print on a work sheet backed by a revoluble platen 25 in the carriage 15. A universal bar 26 cooperates with the type bars 24 to actuate the escapement dogs 20.

Mechanism for driving the carriage in return direction by power includes a drive shaft 27 which is suitably journaled in the framework of the machine and which may be rotated continuously by means of a motor, not shown, during use of the machine. Brackets 28 on the carriage support a rack 29 which meshes with a pinion 30 that is normally rotatably loose on the drive shaft 27, and is slidably rearwardly therealong from the Figure 2 position to engage its clutch teeth 32 with a clutch collar 33 that is fixed to and rotates continuously with the drive shaft 27.

A link 35 is movable rearwardly from its normal position, Figure 2, to slide the pinion 30 rearwardly to clutch the drive shaft 27. The operating connection between said link and pinion comprises rock shafts 36, 37 suitably journaled in the framework, the rock shaft 36 having an arm 38 pivotally supporting the rear end of the link at 39. Said rock shaft 36 has an arm and link connection 40 to the rock shaft 37 which has a shifter arm 41 engaging a groove of the pinion 30 as at 42, Figure 2.

Upon its being shifted rearwardly and thus clutched to the power operated drive shaft 27, the pinion 30 rotates with the latter in the direction of the arrow, Figure 2, and thereby moves the rack 29 rightwardly for returning the carriage. Said rightwardly driven rack 29 initially has limited endwise movement relatively to the carriage before it returns the latter. This initial independent movement of the rack is utilized to line space the platen by means comprising a rack 43 on the rack 29 working through gearing 44 to turn a line spacing shaft 45 journaled in the carriage and forming part of line spacing mechanism of the kind exemplified in the Patent No. 1,835,776 to W. F. Helmond.

In a final part of its power driven return movement to a predetermined position, the carriage 15 displaces a rod 46 slightly endwise to the right of the machine by engaging a carriage return limiting stop connected to said rod as will hereinafter appear. This endwise movement of

said rod 46 is transmitted to the pinion 30 to shift the latter forwardly to unclutch it from the power driven shaft 27. The movement transmitting connections comprise a bracket 47 fastened to said rod 46 and connected by a link 48 to an arm 49 of a rock shaft 50, Figure 1, journaled in the framework of the machine. Said rock shaft 50 has an arm and link connection 51 to the rock shaft 36 of the hereinbefore described carriage-return pinion-shifting train. The rod 46 is slidably supported as at 53, Figure 3, in left and right standards 54 spread laterally from the side wall members 55 of the machine frame. A shaft 56 which is rockable, as will hereinafter appear, is journaled in said standards 54. The usual rack 57 of the Underwood machine for laterally positioning a usual line-end margin stop 58, Figure 6, has end arms 59, Figure 2, supported by but freely rotatable about the shaft for rendering said rack depressible for a purpose which will be referred to later.

The unclutching of the pinion 30 by means of endwise movement by the carriage of a rod such as 46 is shown in my co-pending application Serial No. 57,205, filed January 2, 1936, now Patent No. 2,164,422, dated July 4, 1939. The present application discloses features of improvement over said co-pending application in respect to gaging the return of the carriage to different positions.

The typewriter features and power drive for returning the carriage as so far described are substantially in the prior art as exemplified in the Pitman Patent No. 1,679,741 of August 7, 1928.

I will now describe the organization whereby return of the carriage as by means of the described power drive is selectively gageable to different return or line-start positions at the will of the typist.

There are, for example, three different stations to which the carriage 15 is to be returnable selectively. There is an extreme station in that, of the three stations, it is farthest to the right of the machine, and there are a right intermediate station and a left intermediate station.

Correspondingly, there are three stop devices generally designated, Figures 6 and 7, as ES, RIS and LIS. Figure 7 represents an extension of Figure 6 to the right and hence it will be understood that in the machine the stop devices ES and RIS of Figure 7 are to the right of the stop device LIS of Figure 6.

Each stop device is similar to the carriage return margin stop used in the Underwood typewriter in that it includes a body 60 supported by and slidably along the rod 46 and the shaft 56 and also includes a holding dog 61 pivoted to the body 60 and spring pressed to interlock as at 62 with letter spaced teeth 63 on the rod 46 which thus serves as a stop stationing rack. Each dog 61 has a finger piece 64 by which it is manipulated to retract it from the teeth of the rod 46 preparatory to shifting the stop device laterally to change its carriage return limiting station. The teeth 63 and dog 61 are of ratchet form adapted to lock the stop device positively against rightward displacement by the carriage from its station on the rod 46. Each stop device also includes a pointer 65 cooperative with a letter space scale 67.

For engaging said stop devices, the carriage has secured to its frame a counter-stop 68. The extreme stop device ES has a stop block 69 which preferably is fixed so as to be constantly in the

path of the carriage carried counter-stop 68 as indicated by the dotted line showing of the latter in Figure 7. The intermediate stop devices RIS and LIS include, respectively, stops R and L in the form of arms extending from the rock shaft 56. Each stop arm R and L is slideable along the shaft 56 and has a key 70 and a key retaining screw 71, the key 70 slidably fitting a spline groove 72, Figure 2, in the shaft 56 so that rocking of the latter rocks the stop arms R and L, as will later appear, into and out of the path of the carriage carried counter-stop 68. Each intermediate stop device body 69 has a stop-arm retaining clip 74 so that each stop arm R or L is carried along with the lateral shift of its companion body 69 to one or another station.

Associated with the intermediate stop devices RIS and LIS are corresponding carriage return keys RI and LI. The extreme stop devices ES may also have an associate key CR. These three keys are mounted respectively on corresponding key-levers 76, 77 and 78 and are preferably disposed at the left of the usual typewriter keyboard comprising the type keys 79.

The carriage return keys are selectively depressible to rock their key levers counter-clockwise of Figure 2 about a common fulcrum stud 80 in the framework of the machine. Each of said key levers has an upright arm terminating in a cam end 81. The several cam ends 81 normally stand, side by side, behind a broad pawl nose 82 of a piece 83 pivoted to the link 35 at 84. Said piece 83 has its center of gravity well behind the pivot 84 so that it tends to turn clockwise of Figure 2 but is normally positioned against a stop 85 in the link 35.

A lever 87 pivoted to the framework 18 at 83 is urged clockwise of Figure 4 by a spring 89 and has a lateral spur 90 normally stopping it against said framework as at 91, in such position that a latch spur 92 of said lever 87 engages a shoulder 93 of the link 35 to latch the latter in its normal or forward position, Figure 2. A spring 94 pulls downwardly and rearwardly upon the link 35. Downward movement of the link about its pivot 39 is limited to its normal position, Figure 2, by a vertically adjustable stop 95 on a plate 96 secured to the framework and having a lateral-guide slot 97 for said link 35.

The stop arms R and L have, respectively, counter-stop engaging portions 99 and 100 that are angularly spaced from one another about the axis of the shaft 56. Both stop portions 99 and 100 are normally below the path of the counter-stop 68 as in Figure 2 and are movable selectively into said path by turning the shaft 56 through different angles counter-clockwise of Figure 2.

The shaft 56 is turnable through said different angles by means of the intermediate carriage return keys RI, LI and their respective levers 76, 77. Fulcrumed on the carriage return lever stud 80 is a lever 103 having an arm presenting a transverse pin 104 engageable by either lever 76, 77 as at Figures 2 and 6. A lift arm 106 of said lever 103 has a pin-and-slot connection 107 to a link 108 pivotally connected to an arm 109 fast on a short rock shaft 110 journaled at its opposite ends in the left frame standard 54 and in a bracket 111 attached to the frame, Figures 2, 3 and 6. An arm 112 fast on said rock shaft 110 is connected by a draw spring 113 and a link 114 to an arm 115 fast on the stop arm carrying rock shaft 56. Said link 114 and arm 112 have a pin-and-slot connection 116 which

with the draw spring 113 serves as a one-way yieldable connection whereby counter-clockwise rocking of the shaft 110 rocks the shaft 56 to place the stop arm R or L into the path of the counter-stop 68. This connection is yieldable so that depression of the carriage return key LI and its key lever 77 is not impeded should the stop arm R at that time happen to be directly under the counter-stop 68.

10 The different angular movements of the shaft 56 may be gaged by gaging the angular movement of the lever 76 differently from that of the lever 77 thereby to effect different angular movements of the lever 103 and correspondingly different lifts of the link 108. To gage its angular movement, the lever 76 has an adjustable stop screw 118 for striking a stop plate 119 attached to the framework. To gage its angular movement, the lever 77 has a stop nose 120 to strike said stop plate 119. To limit its stroke, the extreme carriage return lever 78 has a stop nose 121 for striking said stop plate 119.

15 In order that the typist need not keep the key RI or LI depressed to maintain the shaft 56 and its stop arms R and L at the gaged position, said position is maintained automatically by a detent device in the form of a latch lever 122, pivoted at 123 to the lift link 108, and a latch spur 124 attached to the framework as will later be described. The latch lever 122 has two latching steps 125, 126 normally below said spur 124 as in Figure 2.

20 Upon depressing the right intermediate key RI, the link 108 will be lifted just far enough for engaging the upper step 125 of the latch lever with the spur 124 as in Figure 9. In that case, the stop portion 99 of the stop arm R will be placed in the path of the counter-stop 68, but the stop portion 100 of the stop arm L will still be below said path and therefore ineffective.

25 Upon depressing the left intermediate key LI, the link 108 will be lifted farther, that is, for engaging the lower step 126 of the latch lever 122 with the spur 124 as in Figure 10. In that case, the stop portion 100 of the stop arm L will be placed in the path of the counter-stop 68. At the same time the stop arm R will also be in said path but this is of no moment since said stop arm R is to the right of the stop arm L and the latter is effective because it is usually to the right of the counter-stop 68 when the left intermediate key LI is depressed.

30 The extreme carriage return key CR and its lever 78 have no operative connection to the lever 103 and, therefore, at depression of said carriage return key CR, the shaft 56 is not rocked and hence the stops R and L remain below the path of the counter-stop 68 as in Figure 11.

35 Each of the key levers 76—78 has a stop spur 128 against the rear edge of the stop plate 119, as in Figure 2, to determine the normal positions of said key levers in which the latter may be yieldably maintained by individual pull springs 129 anchored to the framework. A spring 130, Figure 2, anchored to the framework, pulls the link 108 downwardly to maintain the latter and its connected parts, including the stop arm shaft 56, and the lever 103 in normal positions, Figure 2, which may be determined by abutment of the transverse pin 104 of said lever 103 with either or both of the stopped levers 76, 77 as in Figure 6. The stop spurs 128 are bendable edgewise for adjusting the normal positions of the levers 76—78. Bending of said spurs 128 is facilitated by providing stiff companion spurs 132 and intermediate

slots 133 on the levers 76-78 for the application of bending tools.

Upon rocking any one of the key levers 76-78 counter-clockwise of Figure 2 by depressing the corresponding key, the corresponding cam end 81 moves forwardly and engages the pawl nose 82 of the piece 83 on the link 35 thereby lifting the latter about the pivot 39 to release its shoulder 93 from the latch spur 92 of the latch lever 87 which is stopped against clockwise rotation at 91. The resulting rearward movement of said link 35 by its spring 94 works as hereinbefore described to shift the carriage return pinion 30 rearwardly to clutch it to the drive shaft 27. Depending on which key is depressed, the stop device ES, RIS or LIS will be effective to intercept the carriage-carried counter-stop 68.

By its rearward movement, the link 35 withdraws a stop 135 thereon rearwardly from its Figure 2 engagement with the latch lever 122 so that the latter urged counter-clockwise of Figure 2 by a spring 136 anchored to the link 108 will engage one of its steps 125, 126 with the latch spur 124, provided either the key RI or LI was depressed to lift said latch lever 122 along with the link 108. If the key CR was depressed, the latch lever 122 is not lifted and hence merely settles against the front of the latch spur 124 with the steps 125, 126 remaining below said spur as in Figure 11.

Upon carriage return limiting engagement of the carriage-carried counter-stop 68 with the effective stop device ES, RIS or LIS, the effective stop device is displaced rightwardly along with the rod 46 so that the latter, by means of the train, Figure 1, rocks the shaft 36 clockwise of Figure 2 to shift the carriage return pinion 30 forwardly from clutching engagement with the drive shaft 27. It will be obvious that said clockwise rocking of the shaft 36 also moves the link 35 forwardly again to cause it automatically to become latched in normal position again by the latch spur 92.

In the forward restoration of the link 35, its stop 135 turns the latch lever 122 clockwise from the Figure 9 or 10 position to release said latch lever from the spur 124. This occurs if it was the key RI or LI that was depressed to render the stop arm R or L effective and it results that there is automatic restoration of the stop arms R and L to normal position, Figure 2, by means of the spring 130 pulling downwardly on the link 108.

The rightward power-disconnecting movement of the rod 46 by the carriage is against a pull spring 138 attached to said rod 46, as at Figure 3, and anchored to the bracket 111. Said rightward movement of the rod 46 and hence of the carriage is ultimately limited by a stop collar 139 on said rod striking the right frame standard 54.

Due to the usual back-lash characteristic of the escapement devices 20, 21, 22, and under the urge of the letter-feeding carriage spring motor 19, the carriage has the usual drop-back movement of approximately a letter space as it becomes disengaged from the carriage return drive shaft 27 by the described rightward movement of the rod 46. This carriage drop-back movement is slightly more than sufficient to enable the spring 138 to return the rod 46 leftwardly to normal position in which a stop collar 140 on said rod 46 strikes the left frame standard 54. The link 48 of the carriage-return-pinion-unclutching train, Figure 1, has a pin-and-slot con-

nexion 141 which, at the carriage drop back, permits the rod 46 to return leftwardly without displacing said train and hence without causing reclutching of the carriage-return pinion 30 with the drive shaft 27.

Figure 8 represents a modification in which right and left intermediate stop arms R' and L' are permanently spaced laterally apart at a fixed distance and are adjustable laterally as a unit along with a companion body 60'. In this construction a spacing block 142 separates said arms R' and L' which, with said block 142 are secured by screws 144 to a broad key plate 143 slidably fitting the spline groove 72 of the shaft 56. A clip 74' engages the stop arm R' to connect the latter, and hence the stop arm L', with the body 60' for lateral shifts as a unit.

Figure 8 also illustrates a modification of an extreme margin stop device ES' having a stop lug 145 positioned to intercept a counter-stop forming tab 146 of a lever 147 pivoted to the carriage frame at 148 so that by rocking said lever clockwise of Figure 8 said tab 146 may be raised clear of said stop lug 145 to permit the carriage to be returned rightwardly beyond said stop device ES'. This latter rightward movement may be limited by said counter-stop tab 146 striking the stop collar 139 on the rod 46. The counter-stop 68 is provided to engage the stop arms R' and L'.

Each of the margin stop bodies 60 or 60' may have a hub sleeve 149 which extends the bearing of the body along the shaft 56.

The latch spur 124 for the latch lever 122 may be a laterally bent tab of a piece 151, Figure 5, pivoted at 152 to a bracket 153 secured to the machine frame 18. Said piece 151 may be turnable about the pivot 152 to adjust the latch spur 124 vertically to thereby adjust the elevation at which the latch lever 122 cooperates to maintain the stop arms R and L.

The lift and consequent release of the link 35 from the spur 92 by operation of the intermediate key lever 76 or 77 are timed to occur in correspondence with the lift at the steps 125, 126 of the latch 122, so said steps will be ready to engage the latch spur 124 immediately upon rearward movement of said link 35. Thus, at rearward movement of the link 35 consequent to operation of the right intermediate key lever 76, the step 125 will have been lifted far enough to be ready to engage said spur 124, and, consequently to operation of the left intermediate key lever 77, the step 126 will have been lifted far enough to engage said spur 124.

The stop 135, on the link 35, controlling the latch lever 122, may be a laterally bent tab of an arm 154 having a screw-and-slot attachment 155, Figure 2, to said link 35 to permit forward or rearward adjustment of said stop on said link.

The line-end margin stop 58 has pivoted thereto at 156 the usual cam lever 157 engageable, as the carriage in its leftward travel reaches an extreme line-end position, by the counter-stop 68 to be thereby rocked clockwise of Figure 6 to depress the rack 57. Said margin stop 58 has a U-shaped clip 158 slidably embracing the rod 46 to keep said margin stop from turning about the shaft 56. Said margin stop 58 is adjustable laterally to different stations and is releasably maintained at any station by means of its spring pressed dog 159 releasably interlocked with the rack 57.

The rack 57 has pivotally connected thereto at 160 at thrust link 161 having a pin-and-slot

connection 162 to the latch lever 87. With the spring 89 maintaining the latch lever 87 stopped at 91 in normal position, the rack 57 is also maintained in normal position preparatory to its depression by engagement of the carriage with the cam lever 157. Such depression of the rack 57 rocks the latch lever 87 counter-clockwise of Figure 4 thereby depressing the latch spur 92 to release the link 35 for consequent carriage-return-initiating rearward movement thereof by 10 the spring 94.

At such rearward movement of the link 35, an inclined cam shoulder 163 thereof rides over the fixed stop 95 thereby lifting the forward end of said link and hence cooperating to lift its pawl nose 82 well over the key lever cam ends 81. This lifting of the forward end of the link 35 may serve through a connection from said link partly shown at 164, Figure 2, to actuate a lock mechanism, not shown, interlocking the type keys 79 with said link. If said interlocking mechanism happens to be effective at a line-end position and hence prevents immediate lifting of the link 35, there is, nevertheless, no opposition to depression of the latch spur 92 by the carriage if the latter at that time should happen to be tabulated and hence moved forcefully to the extreme line-end position. It will be seen, therefore, that provision of the lever 87 as the medium operable by the carriage for releasing the link 35 avoids liability of straining the parts in the contingency just described.

The intermediate carriage return keys RI and LI may be disposed relatively to one another substantially as shown in Figures 2 and 6 so as to be selectively operable by the heel of the palm of the typist's hand, thus leaving the fingers of that hand free to operate the type keys. This method conduces to the typist's speed and convenience in manipulating the keyboard of the 40 machine including said intermediate carriage return keys.

Any one of the three carriage return keys may be released, immediately following its depression, for immediate restoration of the companion key lever to normal position by its spring 129. This immediate restoration of the key lever does not interfere with subsequent automatic forward restoration of the link 35 by means of the carriage inasmuch as the pawl piece 83 of said link 35 may turn counter-clockwise, Figure 2, about its pivot to by-pass the cam end 81 of the restored carriage return key lever. Similarly, if one of the carriage return key levers 76-78 happens to be kept depressed by the typist's hand or finger so that it is not released and restored until after or during the automatic forward return of the link 35, the pawl piece 83 will yield by turning counter-clockwise about its pivot to permit the delayed restoration of the key lever or to permit its restoration concomitantly with the automatic forward restoration of the link 35. Since the link 35 is thus restorable independently of the key levers 76-78, the action of said link 35 to trip the latch lever 122 for determining restoration of the stop arms R and L is also independent of said key levers.

The intermediate carriage return key RI or LI may be operated before the carriage reaches the extreme line-end position defined by the line-end margin stop 58. For example, the carriage may reach said extreme line-end position at only one of a group of lines on a bookkeeping work sheet and be returned automatically to the extreme line-start position at the stop device ES. 75

Succeeding lines of the group may end short of said extreme line-end-position. From said short line-end-position the carriage is to be returnable to one or the other intermediate line-start positions, as, for example, for posting entries in debit and credit columns of said book-keeping sheet.

It will be seen, now, that the invention provides means readily and conveniently operable by the typist for returning the carriage at will to intermediate line-start positions. Further, said intermediate line-start positions may be variably determined independently of one another inasmuch as the intermediate stop devices RIS and LIS are laterally adjustable independently of one another and, moreover, are each adjustable independently of the extreme line start stop device ES, the latter also being adjustable independently to variably determine the extreme line-start position of the carriage. In the Figure 8 modification, the intermediate stop device combining the stop arms R' and L' as a unit is adjustable independently of the extreme stop device ES'.

It will further be seen that the invention is readily applicable to existing forms of machines, such as the Standard Underwood typewriter, for example, with moderate changes in the existing structure of such machine.

Variations may be resorted to within the scope of the invention and portions of the improvements may be used without others.

What is claimed is:

1. In a typing machine; a frame, a carriage movable thereon in advance and return directions, a support on said frame extending adjacent the carriage path and rockable about an axis paralleling said path, a stop on said support and a counter-stop therefor on said carriage for limiting the carriage return movement, means enabling the positioning of said stop selectively at different carriage return limiting stations on said support, a key and key-operated connections for rocking said support for moving said stop transversely of and into the path of said counter-stop, said stop being normally biased to move out of said path, power mechanism responsive to the operation of said key so as to become engaged to drive said carriage in return direction, a detent automatically effective to maintain said support to keep said stop in said path, and means responsive to encounter of said counter-stop with said stop and to consequent lateral displacement of said stop to disengage said power mechanism and release said detent to thereby permit the stop to move out of said path again, said support being adapted to permit said lateral displacement of said stop.

2. In a typing machine; a frame, a carriage movable thereon in advance and return directions, a counter-stop on said carriage, a plurality of carriage-return-limiting stops, means enabling the lateral positioning of said stops individually and separately to different carriage return limiting stations on said frame, a support for said stops movable different extents for moving said stops selectively into the path of said counter-stop, said stops being normally at different distances from said path and being biased to move out of said path, a plurality of keys corresponding to said stops and mounted on said frame stationarily relatively to the lateral positioning of said stops, means individually enabling each key to move said support the requisite extent to move the corresponding stop into said

path, irrespective of the stations of the stops, and power mechanism responsive to the operation of any key so as to become engaged to return the carriage to the corresponding stop.

3. In a typing machine, a frame, a carriage movable thereon in advance and return directions, a power mechanism actuatable for returning said carriage, and means for actuating said mechanism and gaging the consequent return of the carriage to different positions, said means including a plurality of keys, one for each of said positions, mounted on said frame for selective manual operation, means responsive to operation of any key to actuate said mechanism, a rock shaft journaled in said frame, a plurality of stop arms, corresponding to said keys, spaced along said shaft and also spaced angularly about the axis of said shaft, a counter-stop on said carriage, said stop arms being normally out of the path of said counter-stop, and connecting means between said shaft and keys enabling the latter to rock said shaft selectively through different angles to move said stop arms selectively into said path.

4. In a typing machine; a frame, a carriage movable thereon in advance and return directions, a power mechanism actuatable for returning said carriage, and means for actuating said mechanism and gaging the consequent return of the carriage to different positions, said means including a plurality of keys, one for each of said positions, mounted on said frame for selective manual operation, means responsive to operation of any key to actuate said mechanism, a rock shaft journaled in said frame, a plurality of stop arms corresponding to said keys, spaced along said shaft and also spaced angularly about the axis of said shaft, a counter-stop on said carriage, said stop arms being normally out of the path of said counter-stop, connecting means between said shaft and keys enabling the latter to rock said shaft selectively through different angles from a normal position to move said stop arms selectively into said path, detent means acting automatically to maintain said shaft in the position to which it is rocked by a key, and means responsive to the encounter of said counter-stop with a stop arm to stop the carriage returning actuation of said power mechanism and to restore said shaft to said normal position.

5. In a typing machine; a frame, a carriage movable thereon in advance and return directions, a counter-stop on said carriage, a plurality of carriage return limiting stops for engaging said counter-stop, means enabling the positioning of each stop individually and separately at different stations adjacent the path of said counter-stop, a plurality of selectively operable keys corresponding to said stops, means normally maintaining said stops out of said path and operable differently by means of said keys to move said stops transversely of said path to place said stops selectively into said path, power mechanism responsive to operation of any key to become engaged to return the carriage to a position corresponding to the selected stop, a detent automatically effective to maintain the selected stop in said path and means responsive to encounter of said counter-stop and the selected stop to disengage said power operable mechanism and to release said detent to permit said selected stop to be moved out of said path again.

6. In a typing machine; a frame, a carriage movable thereon in advance and return directions a counter-stop on said carriage, a stop

cooperative with said counter-stop for limiting the carriage return movement, a manually operable key, means operable by said key for moving said stop transversely of and thus into the path of said counter-stop, said stop being normally biased to move out of said path, a power operable carriage return mechanism, a normally latched element releasable by operation of said key and displaceable from a normal position to cause said carriage return mechanism to become engaged to return said carriage, means tending to displace said element, said element being returnable to normal latched position to disengage said carriage return mechanism, a latch device automatically effective in response to displacement of said element to maintain said stop in said path, and means responsive to encounter of said counter-stop and stop to return said element to normal position and concomitantly disable said latch device.

7. In a typing machine; a carriage movable in advance and return directions, power operable mechanism engageable for returning the carriage, means for gaging the return of the carriage to an extreme position or to an intermediate position, said means including an extreme stop device and an intermediate stop device, means enabling the positioning of said stop devices individually and separately to different carriage-return-limiting stations, said carriage having counter-stop means for engaging said stop devices, said extreme stop device being normally effective and the intermediate stop device being normally ineffective, means operable to engage said carriage-return-mechanism for returning said carriage to said extreme stop device, a manually operable key, means operable at will by said key to engage said carriage return mechanism and concomitantly render the intermediate stop device effective, a latch automatically effective to sustain effectiveness of said intermediate stop device independently of manually sustained operation of said key, means to render said intermediate stop device ineffective again upon tripping said latch, and means responsive to encounter of said counter-stop means and either one of said stop devices to disengage said carriage-return mechanism, and trip said latch if said key has been operated to render the intermediate stop device effective.

8. In a typing machine having a frame; a carriage movable in advance and return directions on said frame, a counter-stop on said carriage, a plurality of carriage return limiting stops on said frame and spaced apart in the direction of carriage return and also spaced at different distances from the path of said counter-stop, means enabling the stops to be spaced at variable distances apart in said direction, means including a plurality of selectively operable keys to move said stops jointly different distances, the distance depending on which key is operated to place said stops selectively in said path, and power operable carriage return mechanism responsive to operation of any one of said keys to become engaged to return the carriage to the selected stop.

9. In a typing machine having a frame; a carriage movable in advance and return directions on said frame, a counter-stop on said carriage, a plurality of carriage return limiting stops on said frame and spaced apart in the direction of carriage return and also spaced at different distances from the path of said counter-stop, means enabling the stops to be spaced at variable distances apart in said direction, means including

a plurality of selectively operable keys to move said stops jointly different distances, the distance depending on which key is operated, to place said stops selectively in said path, power operable carriage return mechanism responsive to operation of any one of said keys to become engaged to return the carriage to the selected stop, a latch device maintaining the stops automatically in their key placed position, and means responsive to encounter of the counter-stop and selected stop to disengage said carriage return mechanism and to trip said latch device.

10. In a typing machine; a frame, a carriage movable in advance and return directions on said frame, a counter-stop on said carriage, a plurality of carriage return limiting stops individually and separately adjustable at will to different stations along the path of said counter-stop, said stops being, at any station, normally out of said path and at different distances from said path, means including a plurality of keys operative, irrespective of the stations of the stops, to move said stops jointly different distances to place said stops selectively in said path, the distance depending on which key is operated, and power operated mechanism responsive to the operation of any key to become engaged to return said carriage to the selected stop.

11. In a typing machine; a frame, a carriage laterally movable on said frame, a counterstop on said carriage, a plurality of carriage-arresting stops, means including provisions for enabling said stops to be individually and separately adjusted at will to different stations along the path of said counterstop and for disposing said stops, at any station, normally out of and at different distances from said path, a plurality of keys operatively connected to said stops so as to be operable, irrespective of the stations of the stops, to move said stops jointly different distances to place said stops selectively in said path, the distance depending on which key is operated, and a power mechanism responsive to the operation of any key to move the carriage toward the corresponding stop.

12. In a typing machine; a frame, a carriage movable in advance and return directions on said frame, a counter-stop on said carriage, a stop

normally out of the path of said counter-stop, means, including a rack, for placing said stop at different stations along said path, means, including a manually depressible key, for moving said stop into said path, said rack being displaceable endwise by the returning carriage upon encounter of said counter-stop and stop, a power operable mechanism responsive to said key to become engaged to return said carriage to said stop, a latch to maintain said stop in said path independently of sustained manual depression of said key, and means responsive to the displacement of said rack to disengage said carriage return mechanism and to trip said latch.

15. In a typing machine; a frame, a carriage movable in advance and return directions on said frame, power operable carriage return mechanism, a member tending to move in one direction to an operated position to initiate a carriage returning actuation of said mechanism, a latch movable on said frame from a normal position in which it restrains said member, said member being displaceable transversely of said direction to release it from said latch, a key operable to so displace said member, and means enabling the carriage as it reaches a predetermined line-end position to move said latch to release said member independently of said key.

20. In a typing machine; a frame, a carriage movable in advance and return directions, a counter-stop on said carriage, a plurality of carriage return limiting stops jointly movable different distances from a normal position, in which said stops are out of the path of said counter-stop, to place said stops selectively in said path, means, including a plurality of selectively operable keys corresponding to said stops, to jointly move said stops said distances, the distance depending on the key which is operated, power operable carriage returning mechanism, spring-urged means releasable from a normally latched position by any one of said keys to actuate said power mechanism, and a latch device controlled by said spring-urged means to be effective at release of the latter to maintain said stops in their key placed positions.

HENRY L. PITMAN.
